COMBINED MEASURING SPOON SET AND HOLDER THEREFOR

James R. Reichow, St. Paul, Minn., assignor to Brown & Bigelow, St. Paul, Minn.

Application July 22, 1957, Serial No. 47,018

Term of patent 7 years

(Cl. D44—29)

I claim:

The ornamental design for a combined measuring spoon set and holder therefor, as shown.
